Attorney

UNITED STATES PATENT OFFICE

FREDERICK W. ANDREW, OF ANDALUSIA, PENNSYLVANIA, ASSIGNOR, BY MESNE ASSIGNMENTS, TO THE ELECTROLOCK MANUFACTURING COMPANY, OF VICKSBURG, MISSISSIPPI, A CORPORATION OF MISSISSIPPI

ELECTRIC SWITCH

Application filed April 7, 1928. Serial No. 268,302.

My invention relates to electric switches of that character in which a locking means is associated with the switch and in such relation to the contact elements of the switch that the functioning of the latter is controlled by the locking means.

The general object of the invention is to provide a device of the character indicated which is extremely simple in construction and which also is highly efficient for the purposes for which it is designed and intended.

It also is an object of the invention to provide a novel construction and arrangement of means carried by the locking element or means of the device for controlling the switch contact members thereof.

The device is especially adapted for use for controlling the ignition circuits of internal combustion engines, particularly for such circuits employed in the operation of the motors of automobiles and other like vehicles.

In order that the invention may be readily understood and its practical advantages fully appreciated reference should be had to the accompanying drawing, in which I have illustrated an embodiment thereof which is at present preferred by me. However, it is to be understood that the invention is susceptible of embodiment in other forms of construction than that illustrated and that changes in the details of construction may be made within the scope of the claims without departing from the said invention or the principle thereof.

In the drawing:

Fig. 1 is a view partly in longitudinal section and partly in elevation of a device embodying the invention, together with the parts associated therewith and adapted to be controlled thereby;

Fig. 2 is a sectional view taken on the line 2-2 of Fig. 1 and extending longitudinally and centrally of the lock and switch mechanism; and

Fig. 3 is a central, vertical, longitudinal sectional view taken in a plane at right angles to that in which Fig. 2 is taken.

In the drawing I have shown a switch

casing 1 provided with a hollow projection or boss 2 constituting a nipple, in which is secured a tubular sleeve or thimble 3 within which in turn is mounted and connected the adjoining end portion of a conducting wire 4 provided with a wrapping of insulation, as shown, and also one end portion of coils of wire 5 and 6 which constitute protecting means for the said conducting wire 4 and the insulation therefor. The opposite ends of the coils 4 and 5 are permanently secured within a thimble 10 to the outer end of which is secured a tubular member or section 11 which is secured within an opening of the casing of a timer 12. The other end of the conducting wire 4 is connected with a terminal 13 mounted within a bushing 14 of insulating material in the outer end of the tubular member 11 and contacts with a contact member 15 which in turn is connected with the insulated side or member of the interrupting device 16 of the timer, the other side or member of which is grounded, as shown. Any suitable means may be employed for providing the electrical energy or current necessary for the ignition system, but I prefer to employ a storage battery 20 one side of which is grounded as indicated at 21 and the opposite side of which is connected through an ammeter A to one end or side of the primary 22 of a transformer, the other end of which is connected by a wire indicated at 23 to a binding post 24. The secondary 25 of the transformer is connected to the distributor as usual and in known manner. The binding post 24 is mounted within a nipple 26 projecting laterally from the casing 1. The inner end of the binding post 24 is enlarged and is provided with a recess or opening 27 within which is mounted a contact 28 which is held in its outermost position by means of a coiled spring 29 one end of which is seated against the bottom of the opening 27 and the opposite end of which is seated against the bottom of an axial opening in the contact 28. The binding post 24 together with the inner enlarged portion thereof is supported in a

bushing 30 of insulating material within the nipple 26.

The inner end of the contact 28 is held yieldingly in contact with an axially movable contact ring 31 which is held in place upon the inner end of the reciprocatable locking cylinder 35 mounted within a bushing 36 which in turn is mounted within the outer end portion of the casing 1. For the purpose of securing the axially movable ring contact member 31 to the inner end of the reciprocatable lock cylinder 35 I have provided a headed screw 32 which extends through an opening in the bottom of the said contact member 31 and engages the inner closed end of the said lock cylinder, as shown. For the purpose of insulating the contact member 31 from the lock cylinder I have interposed a washer 33 of insulating material between the two, as shown in Figs. 2 and 3, and have also interposed a washer 37 of insulating material between the head of the said screw and the bottom of the contact member 31. Washers 38 and 39 of smaller diameter are interposed between the washer 37 and the head of the screw 32. A coiled tension spring 40 is interposed between the inner end of the casing 1 and the washer 38, previously referred to, and holds or tends to hold the lock cylinder with the parts carried thereby in its outermost position. In such position the contact 28 contacts with the contact member 31 at a point near the inner or rear edge thereof.

The extent of the reciprocatory or back-and-forth movements of the lock cylinder 35 is controlled or limited by a screw 45 which extends through the casing 1 and the bushing 36 and the inner end of which projects into a slot 46 of limited length in the side of the lock cylinder.

The lock cylinder 35 is provided with a barrel 48 having a key slot or opening therein (not shown) for the insertion of a key, by means of which the said barrel may be rotated and the spring pressed plunger 50 withdrawn from its keeper or recess 51 in the inner side of the casing 1. When the locking means is in locking position and the plunger is withdrawn from its keeper by means of a key the spring 40 operates to cause outward movement of the lock cylinder together with the barrel 48 and the plunger 50. When the lock cylinder is in its outermost unlocked position the plunger 50 is held in inward position by reason of the engagement or contact of its outer end with the inner side of the bushing 36.

At such time the contact 55 is in contact with the outer edge of the contact member 31, as illustrated in Fig. 1 of the drawing. The contact 55 is slidably mounted within an axial opening 56 provided in a thimble 57 connected to the adjoining end of the conducting wire 4 previously referred to. The

thimble 57 is mounted within a bushing 60 of insulating material provided in the outer end of the sleeve 3 and is held in position therein by means of a spacer sleeve or bushing 61. A coiled spring 62 mounted within the opening 56 and seated at one end against the bottom of said opening and at its opposite end against the bottom of the axial opening in the contact 55 operates by expansion to hold the said contact outwardly against either the contact member 31 or against the periphery of the inner edge portion of the lock cylinder 35, depending upon whether the lock is in unlocked position, as illustrated in Figs. 1 and 2, or in locked position, as shown in Fig. 3. When in the latter position the conducting wire 4, which is electrically connected at one end to the interrupter 16 as already described, is grounded either through the casing of the lock switch to the metal plate 65 which may be a part of the car body (or at any rate is connected to the car body), or through the sleeve 3 and the coil 5 to the casing of the timer 12.

The casing 1 of the switch is supported upon the metal plate 65 of the car by means of a cup-shaped member 70, the bottom of which is provided with an opening the edges of which are bent outwardly and extended through an opening 71 in the said metal plate and are bent around and in engagement therewith, as shown at 72. The reduced end portion of the lock cylinder 35 projects through the opening formed by the bent edges of the opening in the bottom of the member 70, as illustrated. The outer end portion of the casing 1 is extended into the cup-shaped member 70 and is secured therein by means of headed screws 75 which pass through openings in the side of the said cup-shaped member and engage tapped openings provided in the said casing.

It will be apparent by reference to Figs. 1 and 2 of the drawing that when the locking element of the lock is in unlocked position both of the contacts 28 and 55 are in contact at different points with the contact member 31, which, in the construction as illustrated is of cylindrical form. When, however, the locking means is moved into locked position, as shown in Fig. 3 of the drawing, the contact 55 is disengaged from or is out of contact with the contact 31 and is in contact with the barrel 35 of the lock. When in such position the insulated member or side of the interrupter 16 is grounded.

Having thus described my invention, what I claim and desire to secure by Letters Patent is:

1. A switch for controlling the ignition circuit of an internal combustion engine, comprising a casing, locking means movably mounted within said casing and supporting a contact fixedly connected thereto

and movable therewith, stationary contacts mounted within said casing, said contacts being included within the ignition circuit and both of which are in contact with the 5 said movable contact when the movable locking element is in unlocked position, and one of said contacts being out of contact with the said movable contact when the said locking element is moved into locking position 10 and in contact with the said locking means.

2. An electric switch for controlling the ignition circuit of an internal combustion engine, comprising a casing, locking means longitudinally movable in said casing, a 15 contact element fixedly connected to and movable with the said movable locking means, and stationary contacts located in said casing one of which has connection with a source of electrical energy and the 20 other one of which has connection with the interrupter of a timing device of said circuit, both of the said stationary contacts being in contact with the said movable contact element when the locking means is in unlocked 25 position, the stationary contact which has connection with the said interrupter contacting with the said locking means upon the movement of the said locking means into locked position whereby said contact is 30 grounded.

3. An electric switch for controlling the ignition circuit of an internal combustion engine, comprising a casing, a locking means reciprocatably mounted within said casing, a contact element mounted upon the inner 35 end of the said reciprocatable locking means, stationary contacts mounted within the said casing one of which contacts has connection with a source of electrical energy and the 40 other one of which has connection with the interrupter of the timer of the ignition system, the latter contact contacting with the movable locking means when the latter is moved into locking position whereby the 45 connection to the said interrupter is grounded.

4. An electric switch for controlling the ignition circuit of an internal combustion engine, comprising a casing, locking means reciprocatably mounted in said casing, a 50 contact element mounted upon said locking means and reciprocating therewith, the said element being of cylindrical form, stationary contacts mounted upon said casing and 55 projecting inwardly thereof and adapted to be held yieldingly against the periphery of the said contact element when the latter occupies its outermost position with the locking means in unlocked position, one of the 60 said stationary contacts having connection with a source of electrical energy and the other having connection with the insulated member of the interrupter of the said system, and the latter when the reciprocatable 65 locking means occupies its locked position

contacting therewith whereby the connection with the said interrupter is grounded.

5. An electric switch for controlling the circuit of the ignition system of an internal combustion engine, comprising a casing, a 70 locking means reciprocatably mounted in said casing, a moveable contact element of cup shape mounted upon and insulated from the inner end of the said locking means, means tending to hold the said locking means and the said contact element mounted thereon in their outermost positions in which the said locking means is in unlocked position, stationary contacts mounted upon the wall of the said casing and projecting thereinto, 75 one of said stationary contacts having connection with a source of electrical energy and the other one of which has connection with the insulated side of the interrupter of a timing device, means for yieldingly holding said stationary contacts against different points of the periphery of the said movable contact element when the latter is in its outermost position, and the second contact adapted to engage with the said locking 80 means when the latter is in its innermost locking position whereby the insulated side of the said interrupter is grounded.

6. An electric switch for controlling the ignition circuit of an automobile, comprising a casing, a cup-shaped member mounted upon and having permanent connection with a metal plate constituting a part of the body structure of the automobile, the front end of the said casing projecting into the said cup-shaped member, means for securing the said casing and cup-shaped member together, locking means reciprocatably mounted within said casing and projecting through the said plate whereby it is rendered accessible, a contact element mounted upon said locking means and movable therewith, stationary contacts mounted upon the wall of the said casing and projecting thereinto, one of said stationary contacts having connection with a source of electrical energy and the other having connection with the positive side of the interrupter of the system, both of said stationary contacts being in contact with the said movable contact element when the locking means is in unlocked position and one of the said stationary contacts being out of contact with the said movable contact element when the locking means is in locked position and in contact with the outer side of the said locking means.

In testimony that I claim the foregoing as my invention, I have hereunto signed my name this 4th day of April, A. D. 1928.

FREDERICK W. ANDREW.
